METHOD OF MAKING FAN BELTS

William E. Haggan, Barberton, Ohio, assignor to
The Firestone Tire & Rubber Company, Akron,
Ohio, a corporation of Ohio

Application July 22, 1938, Serial No. 220,729

3 Claims. (Cl. 154—4)

This invention relates to belts, more especially to methods and apparatus for manufacturing fan belts and to the fan belts produced.

Customarily in the manufacture of small belts, such as fan belts, a plurality of belts are simultaneously built upon a drum from sheets of material. In this mass production the reenforcing cord for the finished belt is uniformly wrapped around the drum with the convolutions of the cord being immediately adjacent. Thereafter the individual fan belts are cut from the cylinder of material built upon the drum and certain of the cords are cut and/or exposed. This necessitates covering the fan belts prior to their use for otherwise the cords rapidly fray out from the fan belt and destroy its usefulness.

One object of this invention is to overcome the foregoing and other disadvantages attendant the use of known methods and machines for manufacturing fan belts and, to provide a novel, easily practiced method of constructing fan belts, which method eliminates construction costs of the prior art.

Another object of the invention is to produce a belt in which the reenforcing cords therein are totally embedded in the body of the belt.

Another object is to provide belts which are resistant to transverse compression and circumferential elongation while also being suitably flexible circumferentially.

Another object is to provide apparatus for positioning a predetermined number of cords immediately adjacent each other and then skip an appreciable space prior to depositing a second set of adjacent cords.

The foregoing and other objects are achieved by placing a layer of belt stock upon a collapsible form and winding spaced sets of convolutions of reenforcing cord upon the belt stock. These cords are covered with more belt stock and the individual belts are cut from the form at the portion of the stock between the sets of convolutions of cord. This cuts and/or exposes portions of the reenforcing cords, which portions are secured in the belts in any suitable manner in the process of constructing the belts to prevent them from protruding from the finished belt whereby a belt having the reenforcing cords totally embedded therein can be produced.

In the accompanying drawing;

Figure 1 is an elevation of apparatus for practicing the invention;

Figure 2 is a detail elevation taken on line 2—2 of Figure 1;

Figure 3 is an elevation of a drum used in the

process of constructing fan belts, with a portion of the belt stock plies cut away;

Figure 4 is a perspective view of a portion of the finished fan belts; and

Figure 5 is a detail elevation of the cam means after arcuate movement of the cam with relation to the cam plate has occurred.

Referring specifically to the drawing, a frame 10 is provided to support and journal a threaded shaft 11. The threaded shaft 11 is driven by any suitable means, not shown, which connects thereto at the clutch 12. A threaded sleeve 13 having an annular flange 14 intermediate its ends engages with the threaded shaft 11 and thereby is driven across the threaded shaft 11 by the shaft's rotation. A second, or keyed, shaft 15 carrying a key 16 is also journalled in the frame 10. This shaft 15 is driven in the same direction as the threaded shaft 11 and at a predetermined relative speed thereto through a gear 17 on the threaded shaft. This gear engages with a gear 18 on a shaft 19 which is journalled in a gear positioning arm 21. The arm 21 is rotatably carried by the threaded shaft whereby the relative position of the shaft 19 and the keyed shaft 15 can be varied as desired. The movement of the shaft 19 is limited by an arcuate slot 22 in which the shaft is received. A gear 23 is also carried by the shaft 19 and it engages with a gear 24 on the keyed shaft 15. By varying the position of the shaft 19 in the slot 22, varying sized gears may be substituted for the gear 23 to drive the keyed shaft 15 at a desired relative speed through the threaded shaft 11, and the shafts may be disengaged by such arcuate movement, when desired. In all events, the shaft 11 is driven a predetermined number of complete revolutions faster than the shaft 15 for a purpose later to be explained.

The keyed shaft 15 carries a grooved sleeve 25 which engages with the key 16 and thereby rotates with the shaft 15 although the key connection permits the grooved sleeve 25 to move laterally on the shaft. A substantially U shaped bracket 26 engages with the threaded sleeve 13 and the grooved sleeve 25 and is slidably carried thereby with the arms thereof parallel to the shafts 11 and 15. A carriage member 27 is also slidably carried by the sleeves 13 and 25, being positioned adjacent the forward side of the flange 14 with relation to its normal movement. The bracket 26 carries a guide pulley 28 over which the reenforcing cord is led on to the fan belt stock whereby the bracket 26 must be given the intermittent motion required to lay the re-

enforcing cords, as desired. Cam means are provided to give the bracket 26 such a motion and these means include an annular cam plate 29 which is carried by a base member 31. The base member 31 is secured to the ends of the arms of the bracket 26 so that the cam plate 29 encircles the keyed shaft 15. A cam 32 is carried by and rotates with the grooved sleeve 25. The cam 32 is provided with a predetermined number of small steps, or notches 33 therein which are progressively farther from the base of the cam, the circuit of the cam being completed by the formation of a large step, or notch therein. In the apparatus illustrated, the cam and cam plate each have four steps therein; Figure 1 showing the cam as it initially engages the cam plate, which has a cam surface corresponding to the cam 32. A spring 35 is carried by the grooved sleeve 25 between the bracket 26 and the carriage member 27 to urge the bracket 26 forwardly with relation to the lateral movement of the threaded sleeve 13 and the carriage member 27 associated therewith.

In operation, the threaded shaft 11 drives the threaded sleeve 13 laterally at a uniform rate. Simultaneously the keyed shaft 15 is being rotated at a fraction of the speed of the shaft 11 whereby the cam 32 is retarding the forward movement of the cam plate 29 and the bracket 26 with the threaded sleeve by forcing the cam plate 29 and bracket assembly in the opposite direction with relation to the carriage member 27. The cam's action prevents the forward movement of the guide pulley 28 from being equal to that of the sleeve 13, and compresses the spring 35 for the spring bears upon the carriage member 27 which is held against rearward movement by the flange 14. Then when the large step in the cam 32 is in proper rotative position relative to the cam plate, the bracket 26 is freed for a substantial forward movement. Thus the spring 35, being compressed by the previous cam action, forces the bracket 26 to jump forwardly relative to the movement of the threaded sleeve. This results in a plurality of reenforcing cords 38 being laid immediately adjacent each other either in touching relation or slightly spaced in the fan belt stock, as shown in Figure 3, and then having the apparatus skip an appreciable space prior to again depositing, by winding, a predetermined number of adjacent cords 38. The sleeve 25 offers sufficient resistance to longitudinal movement on the keyed shaft 15 and the spring 35 is readily compressible to prevent the spring from forcing the cam and sleeve 25 forwardly instead of being compressed to the cam's action. However, the cam plate 29 does exert a slight longitudinal force on the cam 32 to aid in moving the sleeve 25 longitudinally on the shaft 15. Figure 3 shows that a number of plies of rubber stock 40 are wound, or otherwise placed upon a collapsible drum, or form, 41 prior to placing the reenforcing cord 38 thereon.

The fan belts are then completed by superimposing at least one ply of fan belt stock upon the reenforcing cords. A feature of the invention resides in the belt stock used for it comprises rubber having countless small fibers 43 embedded therein, the fibers extending transversely of the drum 41. This stock is readily obtained since in milling, or calendering rubber-fiber mixtures, the fibers all are positioned in the direction of passage of the mixture through the mill. Then the milled sheet produced is 75

cut transversely and the strip obtained is positioned on the drum with the fibers 43 running across the drum parallel to the axis thereof.

To cut individual V shaped, in section, fan belts from the cylinder of material prepared on the drum 41, a V shaped piece of rubber 42 must be cut from the cylinder between the sets of reenforcing cords, as shown. Next the drum 41 may be collapsed and the fan belts telescoped 10 from engagement therewith. Obviously the reenforcing cord connecting adjacent sets of cords will be cut when the V shaped rubber pieces 42 are formed and the exposed ends 39 of this cord (Fig. 4) should be cut off or forced into the sides 15 of the fan belt prior to vulcanization so that the finished fan belt has the cords entirely embedded. Cutting the fan belt from the drum 41 will expose the ends of a large number of the transversely extending fibers 43 in the fan belt stock. These ends are highly resistant to wear so that the cross-section of the fan belt is not appreciably reduced with extended use. Thus 20 the fan belt retains the same radial position on the V shaped pulley seat in which it usually is received whereby the belt does not rapidly wear loose after being initially made taut. The fibers extending transversely of the belt make it quite 25 resistant to sidewise bending and transverse compression, but do not stiffen the belt to circumferential bending, which is an essential property of the belt. The reenforcing cord is stretched prior to being wound upon the drum 41 so that it maintains the circumference of the fan belt constant. The resistance to transverse compression 30 obviates the tendency for the belt to be squeezed to a narrower width as it passes over a V pulley, and thus avoids undesirable apparent lengthening or stretching in a circumferential direction.

40 It will be observed that the number of cords deposited adjacent each other can readily be varied by changing the relationship of the cam plate and cam and by varying the relative rotation of the shafts 11 and 15 and, preferably, the 45 number of notches in the cams. The spacing between the sets of cords can also be controlled in this manner and by the pitch of the threads cut on the shaft 11.

Figure 4 shows a fan belt when it is completely 50 assembled and indicates how a set of seven cords are deposited immediately adjacent and then a space is skipped prior to depositing the second group of cords.

An overrunning clutch 45 is connected in the 55 shaft 15 to prevent it from rotating when the shaft 13 and bracket 26 are returned to their starting positions by reversing the rotation of the shaft 11.

Sometimes it may be desirable to cut the reenforcing cord extending between the sets of convolutions before the cord is covered with rubber. Then the ends of the reenforcing cord would be secured immediately adjacent, or contacting, the sets of convolutions before covering the reenforcing cords with the next ply. In all events, the invention provides apparatus by which reenforcing cords can be deposited in fan belt stock in such a manner that fan belts having reenforcing cords entirely embedded therein can be produced.

In accordance with the patent statutes, I have illustrated and described the structure and method of constructing an embodiment of the invention. However, it will be understood that various modifications can be made without departing

from the scope of the invention as defined in the appended claims.

I claim:

1. In a process for manufacturing belts, the steps of placing a layer of belt stock upon a collapsible drum, winding spaced sets of adjacent convolutions of a continuous reenforcing cord upon the surface of the belt stock, superimposing belt stock upon the reenforcing cords, cutting the built up belt stock into a plurality of annular bands at the portion of the belt stock between the sets of convolutions of reenforcing cords, and inserting the exposed portions of the reenforcing cords into the sides of the annular bands whereby a belt having reenforcing cords totally embedded therein can be made. 15

2. In a process for manufacturing belts, the steps of placing a layer of belt stock upon a collapsible drum, winding spaced sets of adjacent convolutions of a continuous reenforcing cord upon the surface of the belt stock, superimposing belt stock upon the reenforcing cords, thereafter cutting the built up belt stock into a plurality of annular bands at the portion of the belt stock between the sets of convolutions of re- 25

enforcing cords, separating the bands to expose a portion of the cord originally extending between the sets of convolutions thereof and cutting off the exposed portions of the reenforcing cords whereby a belt having reenforcing cords totally embedded therein can be made. 5

3. In a process for simultaneously manufacturing a plurality of reinforced belts upon a collapsible smooth surfaced drum, the steps of applying a sheet of belt material to the drum, winding spaced sets of adjacent convolutions of a continuous reenforcing cord upon the drum, cutting the reenforcing cord connecting the sets of convolutions, securing the ends of the reenforcing cord immediately adjacent the sets of convolutions thereof to form a circumferential space which has no cords thereon, covering the sets of convolutions of reinforcing cord with a rubber sheet to form a laminated cylinder of belt material, and cutting the cylinder into individual bands at the portion thereof between the sets of reinforcing cords whereby a belt having reinforcing cords totally embedded therein can be produced. 10
